CLAIM

The ornamental design for a combined monitor, video tape recorder and camera, as shown and described.

DESCRIPTION

FIG. 1 is a top, front and left side perspective view of a combined monitor, video tape recorder and camera according to our design;

FIG. 2 is a top, rear and left side perspective view thereof;

FIG. 3 is a front elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a rear elevational view with the monitor and video tape recorder section rotated 180° relative to the camera section; and,

FIG. 9 is a view similar to FIG. 1 with the monitor and video tape recorder rotated 180° relative to the camera section.
